(57) **CLAIM**

The ornamental design for a motorbike front fork with fender, as shown and described.

DESCRIPTION

FIG. 1 is a top perspective view showing environmental structure of the top, rear, and right sides of a motorbike front fork with fender;

FIG. 2 is a top perspective view showing environmental structure of the top, front, and left sides of the motorbike front fork with fender;

FIG. 3 is a top perspective view showing the top, front, and left sides of the motorbike front fork with fender;

FIG. 4 is a top perspective view showing the top, rear, and right sides of the motorbike front fork with fender;

FIG. 5 is a right side elevation view of the motorbike front fork with fender;

FIG. 6 is a left side elevation view of the motorbike front fork with fender;

FIG. 7 is a front elevation view of the motorbike front fork with fender;

FIG. 8 is a rear elevation view of the motorbike front fork with fender;

FIG. 9 is a top plan view of the motorbike front fork with fender; and,

FIG. 10 is a bottom plan view of the motorbike front fork with fender.

The broken line showing of portions of the motorbike are provided for the purpose of illustrating environmental structure and form no part of the claimed design.

1 Claim, 6 Drawing Sheets
